UNITED STATES PATENT OFFICE.

GEORGE HAMES, OF CHELSEA, MASSACHUSETTS.

WARP STOP-MOTION FOR LOOMS.

1,058,860.

Specification of Letters Patent. Patented Apr. 15, 1913.

Application filed May 1, 1912. Serial No. 694,336.

To all whom it may concern:

Be it known that I, GEORGE HAMES, a citizen of the United States, residing at Chelsea, in the county of Suffolk and State of Massachusetts, have invented new and useful Improvements in Warp Stop-Motions for Looms, of which the following is a specification.

This invention relates to improvements in electric warp-stop mechanism for looms.

The invention is especially adapted to be used in looms constructed and adapted to weave elastic fabrics such as are used in the manufacture of surgical bandages, garters and suspenders.

My invention has for one of its objects the provision of simple and effective electrical appliances for automatically stopping the loom when a warp or other thread breaks.

Electrical stop-motions for looms are well known. In one of the most ordinary forms drop wire detectors are attached to each of the warp threads and the loom is so constructed that when one of these warps breaks or becomes loosened the drop wire falls upon some metal part and completes an electric circuit which in turn operates by means of an electro-magnet to shift the belt operating the loom and thus cause the loom to stop.

My invention relates to this general form of device but embodies several important improvements thereon.

In all devices previous to mine the electric circuit is completed by the contact between the drop wire detector and some other metal part. In the operation of all looms a great amount of light fluff and lint is thrown off, and as this settles in a downward direction a portion of it naturally falls on the metal plate or other object in which the drop wires come in electric contact thus causing the apparatus to fail to work or to fail to work dependably. This defect is increased and aggravated in the case of that class of looms employed in weaving elastic webbing. In elastic fabric the warps are usually threads of rubber. In order to put these rubber threads in proper condition to be woven into a fabric it is necessary to cover them with a fine clay and the result is that in the weaving operation, in addition to the fluff and lint being thrown off by the cotton weft threads, as is the case in the weaving of any fabric, the rubber threads throw off a large amount of white clay, above mentioned, and also considerable rubber dust. This causes insu-

lation to take place between the points of electrical contact between the drop wire detectors and the plate on which they fall more quickly and thoroughly than in ordinary looms, in fact, this difficulty is so great that in practical operation users of the looms for weaving the elastic fabric have largely given up the use of electric stop-motions for these looms and are relying upon some form of mechanical stop-motion.

By my invention I provide a loom wherein the drop wire detectors fall upon a pivoted electric switch which is normally open and by their weight depress the switch and close the circuit. The point of electrical contact is not where the drop wires fall upon the switch but is placed in some protected position where the accumulation of fluff, lint, clay and rubber dust is very much less, so much so that danger of insulation is practically done away with, and I have found my invention works perfectly in connection with these looms.

Another object of my invention is to provide simple and efficient and positive means whereby when the electric current has been completed and has performed its function by stopping the loom, the said current is at once automatically broken thus saving any further and unnecessary action of the batteries.

A third object of my invention is to provide an improved means for shifting the belt, supplying power to the loom, thus stopping the same when the electrical current is made by the switch above mentioned.

The invention consists in the combination and arrangement of parts set forth in the following specification and particularly pointed in the claim.

Referring to the drawings: Figure 1 is a side elevation of an elastic fabric loom equipped with the electric stop motion of my invention, broken away and shown partly in dotted lines, with parts not essential to my invention omitted. Fig. 2 is a detail front elevation showing the belt shifting rod and the connecting levers. Fig. 3 is a detail view of a portion of my invention showing a group of drop wire detectors supported on warp threads, guide brackets for said detectors and the electric switch. Fig. 4 is a plan view of the electric switch.

Like numerals refer to like parts throughout the several views of the drawing.

In the drawing 10 is the frame of an elastic fabric loom, 11 is the lay of the loom, 12 is one of the warp threads to be used in the process of manufacture of the fabric. 5 The warp thread 12 is unwound from a spool or reel 13 and passes over the back girt 14 through the heddle 15 and lay 11. The drop wire detector 16 is hung by means of a hook 17 formed on the top thereof, over 10 the warp thread 12 nearly contiguous with the back girt 14. It is to be of course understood that there are many warp threads and drop wire detectors. A bracket 18 is fastened to the lower side of the back girt 14 and extends downwardly therefrom. To 15 this bracket is pivoted the electric switch 19 by means of a pivot 20. The electric switch 19 comprises two parts, the tread portion 21 and the electric contact portion 22. 20 The tread portion 21 extends at right angles to the other part of the switch and is long enough to project beneath all of the detectors on the loom. This tread portion 21 is so positioned that any drop wire which 25 comes displaced by the breaking or loosening of the warp 12 will fall thereon. The drop wires 16 are guided by the brackets 23 which prevent them from any falling motion except a directly downward one. The 30 tread 21 is made of a sufficient width to insure the drop wire detectors 13 striking it upon any displacement. The contact portion 19 is situated on the opposite side of the switch from the tread portion 21 relatively to the pivot 20 and it is located immediately under the back girt 14. This contact portion is weighted by the part 24 so that when in normal position, that is, when 35 no drop wire is resting on the tread portion, 40 it shall tip downwardly and thus keep the switch open. The weight at this end, however, is only slightly greater and the difference in weight is overcome if even one of the drop wire detectors drops on the tread 45 portion 21, and when this happens the contact portion 22 moves upwardly and comes in contact with the contact plate 25 thus completing the electric circuit.

It will be noted that the point on the 50 switch 19 where electric circuit is completed, that is, the point where the contact portion 22 engages the contact plate 25, lies well under the large back girt 14 which forms an effective shield to protect the contact 55 portion 19 and contact plate 25 from the falling and settling fluff, lint, clay and rubber dust thrown off in the operation of the loom.

An electro-magnet 26 is secured to the 60 frame 10, and 27 is a rocker arm pivotally secured to the frame 10. Pivotally secured to the rocker arm 27 is an armature 28, 29 is a bolt slidably mounted on the rocker arm 27 and connected with the armature 28 by a 65 connection 30, 31 is a shipper rod adapted

to shift the driving belt of the loom from the fast to the loose pulley and vice versa. The rocker arm 27 is connected with one end of a bell crank lever 33 by a link 32 and to the other end of the lever is attached a 70 link 34 connecting said lever 33 with another bell crank lever 35 which is in turn connected with the shipper rod 31. Attached to the lay 11 is the bunter 36, 37 is a circuit breaker fast to the frame 10 and 75 adapted to be in contact with the bell crank lever 35 when the loom is in operation but out of contact when the loom is not in operation. Batteries 38 are provided for generating an electrical current which is adapted to 80 pass (when the circuit is closed by the switch 19 and circuit breaker 37) through the wire 39, bracket 18, switch 19, contact plate 25, wire 40, electro-magnet 26, wire 41, circuit breaker 37, and from the circuit breaker 37 85 through the lever 35, the frame 10 and the wire 42.

The operation of a loom equipped with my invention is as follows: When the loom 90 is in operation and the warp threads 12 are all unbroken and under tension, the drop wire detectors 16 are all held suspended and the switch 19 is open. If one or more of the warp threads 12 become broken or unduly 95 loose the drop wire detectors attached to such threads will fall upon the tread 21 thus causing the switch 19 to swing on its pivot and close the circuit at contact plate 25. The current passing to the electro-magnet 26 100 will energize the same. The electro-magnet will then attract the armature 28, which will in turn move the sliding bolt 29 upwardly. When the sliding bolt 29 is moved to its extended position the bunter 36 on the 105 lay 11 will strike the said bolt during the beat of the lay. It will be observed that when the sliding bolt 29 is in its retracted position the lay is free to pass over the end of the rocker arm 27 without engaging the 110 same in any way. When the bunter 36 strikes the sliding bolt 29 in its extended position it causes the rocker arm 27 to swing on its pivot and this motion in turn operates the link 32, lever 33, link 34 and lever 35 115 to move the shipper bar 31 inwardly and thus shift the belt from the fast to the loose pulley, thus stopping the action of the loom. When the shipper bar 31 moves to shift the belt and stop the loom it breaks the contact 120 which before existed between the circuit breaker 37 and the bell crank lever 35 and breaks the electric circuit. When the loom is thus automatically stopped the operative will of course proceed to repair the damaged 125 warp threads which caused the stop and when the same are repaired will again hang in position the drop wire detectors 16 which were displaced by the breaking of the warps. To again start the loom, the operative moves 130

the shipper bar 31 by hand to throw the belt from the loose to the fast pulley. When this is done the bell crank lever 35 again comes into contact with the circuit breaker 37 thus completing the electrical connection at that point. At this stage, however, the circuit is open because the switch 19 is out of contact with the contact plate 25. This break is occasioned by the fact that when 10 the operative lifts the drop wire detectors 16 he removes the weight from the tread portion 21 of the switch 19 and the said switch falls of its own weight into an open position.

15 Having thus described my invention, what I claim and desire by Letters Patent to secure is:

An electric stop motion for looms having in combination a loom frame, a rocker arm 20 pivoted thereto, an electro-magnet, means to

energize said magnet upon warp fault, an armature pivoted to said rocker arm, a stop bolt slidably mounted on said rocker arm and connected with said armature, a belt shipper for said loom, means to connect said belt shipper and said rocker arm, a loom lay provided with a bunter adapted to engage said sliding bolt whereby when said electro-magnet is energized said armature is moved toward said magnet and said sliding bolt is extended into a position to be engaged by said bunter on the said lay and said shipper belt is moved to stop said loom.

In testimony whereof I have hereunto set my hand in presence of two subscribing witnesses.

GEORGE HAMES.
